UNITED STATES PATENT OFFICE

JOSEPH J. BAUMAN, OF CHICAGO, ILLINOIS

DESIGN FOR A COSMETIC JAR

Application filed April 1, 1931. Serial No. 39,329. Term of patent 3½ years.

To all whom it may concern:

Be it known that I, JOSEPH J. BAUMAN, a citizen of the United States, residing at Chicago, in the county of Cook and State of Illinois, have invented a new, original, and ornamental Design for a Cosmetic Jar, of which the following is a specification, reference being had to the accompanying drawings, forming part thereof.

I claim:

The ornamental design for a cosmetic jar as shown.

JOSEPH J. BAUMAN.
